US00D592098S

(12) **United States Design Patent**
Petit

(10) **Patent No.:** **US D592,098 S**
(45) **Date of Patent:** **** May 12, 2009**

(54) **SNOWMOBILE**

(75) Inventor: **Philippe Petit**, Orford (CA)

(73) Assignee: **BRP Finland Oy**, Rovaniemi (FI)

(**) Term: **14 Years**

(21) Appl. No.: **29/298,601**

(22) Filed: **Dec. 7, 2007**

(51) LOC (9) Cl. **12-14**

(52) U.S. Cl. **D12/7**

(58) **Field of Classification Search** **D12/7, D12/8, 9, 10, 110, 111, 112, 307, 400, 86, D12/85, 88, 11, 159, 162, 168, 169, 172, D12/173; D21/533; 180/182, 190, 184-186, 180/9.25, 180, 219, 193, 194; D6/354; 280/845**

See application file for complete search history.

(57) **CLAIM**

The ornamental design of a snowmobile, as shown and described.

DESCRIPTION

FIG. 1 is a front left perspective view showing a snowmobile according to my design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

Throughout the Figures, broken lines showing structure are for illustrative purposes only and form no part of the claimed design. Portions of the snowmobile not shown in the Figures form no part of the claimed design.

1 Claim, 5 Drawing Sheets
